Primary Examiner — Marcus A Jackson

(**) Term: **15 Years**

(57) **CLAIM**

The ornamental design for an LED light bar, as shown and described.

(21) Appl. No.: **29/779,289**

DESCRIPTION

(22) Filed: **Apr. 19, 2021**

FIG. 1 is a perspective view of an LED light bar showing my new design;

(51) **LOC (13) Cl. 26-04**

FIG. 2 is another perspective view thereof;

(52) **U.S. Cl.**

FIG. 3 is a front elevational view thereof;

USPC **D26/1**

FIG. 4 is a rear elevational view thereof;

(58) **Field of Classification Search**

USPC D26/1-4

See application file for complete search history.

FIG. 5 is a left side elevational view thereof;

(56) **References Cited**

FIG. 6 is a right side elevational view thereof;

U.S. PATENT DOCUMENTS

FIG. 7 is a top plan view thereof;

D528,672 S * 9/2006 Nagai D26/1

FIG. 8 is a bottom plan view thereof;

D535,037 S * 1/2007 Kim D26/1

FIG. 9 is an exploded perspective view of the led light bar;

D562,473 S * 2/2008 Matsui D26/1

and,

D570,506 S * 6/2008 Uemoto D26/1

FIG. 10 is an enlarged view of portion 10 shown in FIG. 1.

D594,576 S * 6/2009 Chan D26/1

The LED light bar is shown with a symbolic break in its length and the appearance of any portion of the LED light bar between the break lines form no part of the claimed design. The broken lines in the drawings depict portions of

D747,008 S * 1/2016 Kim D26/1

the LED light bar that form no part of the claimed design.
